UNITED STATES PATENT OFFICE.

JAMES H. SAGER AND GEORGE D. GREEN, OF ROCHESTER, NEW YORK.

CUSHION-FRAME FOR BICYCLES OR LIKE VEHICLES.

SPECIFICATION forming part of Letters Patent No. 707,262, dated August 19, 1902.

Application filed January 18, 1902. Serial No. 90,286. (No model.)

To all whom it may concern:

Be it known that we, JAMES H. SAGER and GEORGE D. GREEN, citizens of the United States, and residents of Rochester, in the county of Monroe and State of New York, have invented certain new and useful Improvements in Cushion-Frames for Bicycles or Like Vehicles, of which the following is a specification.

This invention relates to cushion-frames for bicycles and like vehicles, and has for its object to relieve riders of such vehicles from the jarring and shaking ordinarily occasioned by rough roads and obstructions encountered in the road.

The peculiar features of the invention are disclosed in the drawings and are particularly pointed out in the following specification.

Figure 1 of the drawings shows in side elevation a part of the frame of a bicycle, the position of the rear wheel and the location of certain parts being indicated by dotted lines; and Fig. 2 is partly a section on the line 2 2 of Fig. 1 and partly a rear view of a portion of the frame broken away, so as to show the construction.

A represents the front section of the frame, with the exception of the head, which is not shown.

B is the horizontal barrel, which is the crank-hanger; C, the rear-wheel fork, which is rigidly connected with the hanger B, and D the rear braces, which are each flexibly connected with a member of the fork C, as by the bolt d.

D' is a brace for the rear braces D. The hanger B, the fork C, and the braces D constitute what will hereinafter be referred to as the "rear section" of the frame. The front and rear sections of the frame are flexibly connected at the hanger B, as by ears b and the bolt b'. The sections of the frame are also flexibly connected at the upper ends of the braces. A clip or bracket E, rigidly secured to the front section, supports a cross-bar whose ends rest upon springs within the braces D D. This cross-bar is in the construction shown composed of the blocks F F, which are supported by means of arms G G, respectively, which in turn lie within the socket e in the clip E and which are adjust-

ably fastened together, as by the screw g. The blocks F F are adapted to fit within the tubular braces D, respectively, so as to slide 55 freely within them, and are enabled to slide within said braces by the longitudinal slots d' d', which receive and permit the passage of the arms G G, respectively. At the point where the arms G G join the rods F they are 60 cut down, as shown in Fig. 2, so that the slots d' d' may be narrower than they otherwise would be.

The adjustable connection of the blocks F F, as by means of the screw g, obviates 65 the necessity of accuracy in the construction of the arms with reference to the distance between the braces D D which otherwise would be necessary in order to secure the effective operation of said blocks within said braces. 70 The separable connection within the arms G G afforded by the screw g also enables the parts to be readily assembled and taken apart.

Within the tubular braces D D are respectively two coiled springs H H, which may be seated at the lower ends of said braces, respectively, or in any suitable manner, as on a pin d³. (See Fig. 1.) The tubular braces D D are represented as straight and parallel for their full length in order that springs of 75 maximum length may be employed. The upper ends of these springs lie, respectively, against the blocks F F and are preferably under slight tension when in their normal position, (shown in Fig. 2,) so that the parts 80 will not rattle. Stops of suitable form, such as caps D² D², are screwed into the tops of the tubes D D, respectively, and a packing d² d², of rubber or other suitable material, is placed within said tubes D D, respectively, 85 beneath the caps D² D² to receive the rebound of the blocks E E when the springs H H are relaxed.

The operation of the device is as follows: When by reason of the roughness of the road 95 or of an obstruction encountered by the wheels the weight of the rider is brought suddenly upon the frame, the front section will turn upon its lower pivotal connection with the rear section at the hanger and the blocks 100 F F will sink down into the tubular braces D D against the yielding resistance of the springs H H, said tubular braces and blocks F F at the same time alining themselves to

each other by turning at the point where they are respectively connected flexibly with the fork C and the bracket E. By this construction very long coiled springs may be employed 5 which will give great elasticity to the frame, for the springs may, if desired, be extended down into said braces for practically their whole length, and at the same time a construction is had in which the seat-post and 10 saddle can be placed well down upon the frame.

What we claim is—

1. The combination of a rigid front section; a rear-wheel fork flexibly connected therewith at the crank-hanger; tubular rear braces 15 flexibly connected with said fork; a slot in each of said braces at its upper end; a spring within each of said braces; a seat for the bottom of each of said springs; a cross-bar flexibly connected with the front frame and passing through said slots; a block within each 20 of said braces resting on the spring in the brace and secured to said bar and free to slide within said brace; and a stop in each brace 25 above the block.
2. The combination of a rigid front section; a rear-wheel fork flexibly connected therewith at the crank-hanger; parallel tubular braces flexibly connected with said fork; a slot in 30 each of said braces at its upper end; a spring within each of said braces; a seat for the bottom of each of said springs; a cross-bar flexibly connected with the front frame and passing through said slots; a block within 35 each of said braces resting on the spring in the brace and secured to said bar and free to slide within said brace; and a stop in each brace above the block.
3. The combination of a rigid front section; 40 a rear-wheel fork flexibly connected therewith at the crank-hanger; tubular rear braces flexibly connected with said fork; a slot in each of said braces at its upper end; a spring within each of said braces; a seat for the bottom of each of said springs; an adjustable 45 cross-bar flexibly connected with the front frame and passing through said slots; a block within each of said braces resting on the spring in the brace and secured to said bar and free 50 to slide within said brace; and a stop in each brace above the block.
4. The combination of a rigid front section; a rear-wheel fork flexibly connected therewith at the crank-hanger; tubular rear braces 55 flexibly connected with said fork; a slot in each of said braces at its upper end; a spring within each of said braces; a seat for the bottom of each of said springs; a separable cross-bar flexibly connected with the front frame 60 and passing through said slots; a block within each of said braces resting on the spring in the brace and secured to said bar and free

to slide within said brace; and a stop in each brace above the block.

5. The combination of a rigid front section; 65 a rear-wheel fork flexibly connected therewith at the crank-hanger; tubular rear braces flexibly connected with said fork; a slot in each of said braces at its upper end; a spring within each of said braces; a seat for the bottom of each of said springs; a bracket rigidly connected with the front frame; an adjustable cross-bar revolvably supported within 70 said bracket and entering said slots; a block within each of said braces resting on the spring 75 in the brace and secured to said bar and free to slide within said brace; and a stop in each brace above the block.

6. The combination of a rigid front section; 80 a rear-wheel fork flexibly connected therewith at the crank-hanger; tubular rear braces flexibly connected with said fork; a slot in each of said braces at its upper end; a spring within each of said braces; a seat for the bottom of each of said springs; a bracket rigidly 85 connected with the front frame; a separable cross-bar revolvably supported within said bracket and entering said slots; a block within each of said braces resting on the spring in the brace and secured to said bar and free 90 to slide within said brace; and a stop in each brace above the block.

7. The combination of a rigid front section; a rear-wheel fork flexibly connected therewith at the crank-hanger; the tubular braces 95 D, D, flexibly connected with said fork and having respectively longitudinal slots d', d'; the bracket E; blocks F, F, free to slide within said braces; arms G, G, rotatively secured within said bracket and attached to said 100 blocks; springs H, H, inclosed within said braces respectively and a stop in each brace above the block, substantially as shown and described.

8. The combination of a rigid front section; 105 a rear-wheel fork flexibly connected therewith at the crank-hanger; the parallel tubular braces D, D, flexibly connected with said fork and having respectively longitudinal slots d', d', the caps D², D², in the top of said 110 tubular braces, the bracket E rigidly secured to the front section; arms G, G, rotatively secured within said bracket; the screw g for adjustably connecting said bars; blocks F, F, free to slide within said braces; springs H, H, 115 within said braces, and seats for said springs respectively, substantially as shown and described.
